GEARING FOR TEXTILE-PRINTING MACHINES

Application filed October 12, 1929. Serial No. 399,266.

This invention relates to machines for color printing of any material, on a rotary type machine using intaglio copper rolls.

The principal objects of the invention are to provide for eliminating the removal of the intermediate gear for changes in circumference of the printing rollers, and in fact to eliminate the necessity of having a stock of intermediate or star gears of different sizes; to provide an adequate combined gear guard and stud reinforcement; to provide adjustable guards for the bites of the fitting gears; also to obviate the necessity of bringing the driving pinion back into mesh with a new intermediate gear of a different size, which is a troublesome and pains-taking operation; to provide an improved change speed device for running the intermediate or star gear; to provide a simple and convenient device for setting and holding the intermediate pinions in adjusted position, and to provide an arrangement whereby a single intermediate gear will accommodate the greatest range in the size of the printing rollers that will be needed for ordinary work.

Other objects and advantages of the invention will appear hereinafter.

Reference is to be had to the accompanying drawings in which

Fig. 1 is a side view partly in section of a printing machine constructed in accordance with this invention;

Fig. 2 is an enlarged side view of the change speed mechanism;

Fig. 3 is an edge view of the same;

Fig. 4 is a side view, on enlarged scale, with parts omitted;

Fig. 5 is a sectional view on the line 5—5 of Fig. 4;

Fig. 6 is a sectional view on the line 6—6 of Fig. 4;

Fig. 7 is a side view of an individual gear guard, and

Fig. 8 is an edge view thereof.

This machine is designed as an improvement over the well-known type of color printing machines employing the intaglio process. As these machines are usually made, power is received from a shaft 10 which is driven in any desired way and is mounted adjust-

ably on an inner bearing and an out-board bearing, not shown, but which has always been made adjustable to accommodate different sizes of intermediate gears.

On this shaft 10 in this case is a gear 9 which, in the position shown in Figs. 2 and 3, meshes with a gear 7 which drives the intermediate or star gear 11. On the opposite side of the gear 9 is a smaller gear 6 not touching it, in the position shown. Integral with the gear 6 is a larger gear 5. The gear 9 is movable axially by a handle 4 so as to mesh, as shown, with the gear 7 in one position and with the gear 5 in the other. The gears 5, 6 and 7 are located on an oscillating frame 3 which is not slidable, but it is turned by the worm 2. By this the gear 6 can be brought into mesh with the gear 11. The handle 4, on being moved to dotted line position in Fig. 3, slides the gear 9 into mesh with the gear 5. This changes the speed. A platen cylinder 12 is mounted on a shaft concentric with which, on a shaft 8, the intermediate gear 11 is mounted to rotate freely.

The gear 11 does not mesh directly with a series of roller gears 13 as usual, one on the shaft of each of the color rollers 14. Obviously when the diameters of the color rollers have to be changed, the intermediate gear in such case would also have to be changed unless, of course, the change of diameter is so slight as to allow for a little more separation, and the operation of the gears 13 by a looser fit, which would not result in good printing. The main or platen cylinder 12 is driven by surface contact with the rollers 14 which are positively driven.

The printing or color rollers are changed frequently for ones of different diameter and this change would be responsible for several inconveniences. First it would necessitate the removal of the intermediate gear 11 and its replacement by one of a different size in order to insure the contact of the printing rollers 14 with the platen cylinder 12. Of course, this would be necessary because the cylinder was driven by contact with them.

This operation of removing and replacing the intermediate gear was inconvenient at 100

all times but particularly so on machines having a large number of color rollers, also any replacement of this gear due to accidental breakage was very expensive. If the 5 gear was not replaced, due to the fact that the change in the size of the gears 13 might be very small, good driving was not secured because the intermediate gear would engage only the ends of the teeth of the gears 13 and chattering would occur, which would 10 affect the quality of the printing and shorten the life of the gears. Furthermore, it was necessary for the user of this machine to keep a large number of intermediate gears 15 in stock, which is an expense in several ways as will be obvious.

Another very serious difficulty was that, when the intermediate gear was changed it was necessary to bring the driving gear 9 20 into mesh with it, which was done by moving its shaft 10. This was provided for by slots in the bracket which holds the out-board bearing and also the in-board bearing, but was a troublesome operation, as these 25 two bearings had to be adjusted separately and to the same extent. It should be obvious that to perform this adjustment and keep the bearings in alignment, with a heavy gear on the shaft, was a very troublesome operation.

The above is mostly, except the change speed device, a description of the type of machine on which this invention is an improvement. By this invention each of the 35 rolls 13 is connected with and driven from the intermediate gear 11 by a pinion 16. It will be seen that the reversal of the direction of rotation of the rolls 14 by the use of the extra pinions 16 is compensated for 40 by the use of the extra gear 7 or 5 for driving the gear 11 so no change in the direction of rotation of the driving shaft 10 or of the color rollers has to be made over the usual practice. The gear 11 is permanent 45 and is mounted in stationary bearings.

In order to accomplish this result, a supporting sector shaped sub frame 18 and a cover frame 25 are provided centered on the shaft 8 and adjustably mounted about it by 50 the use of slots 19 and securing bolts 20 connected to the frame of the machine. The cover frame 25 extends back over the gear 16 to cover them entirely. This has not been possible heretofore, but can be done with this 55 way of supporting them. They also act to steady and reinforce the studs. These frames are adjusted by screws 21 passing through lugs on the frame in a simple manner. This subframe and cover frame are 60 provided with a series of slots 22 for receiving the studs 23 on which the pinions 16 are mounted. The rolls 14 are adjusted individually by their screws 24.

As it is not possible to set the frames and 65 gears in absolutely correct position for all

sizes of roll, these slots 22 are elongated and after the gears are set in position, doweled washers 26 are set on at both sides of the studs 23 and secured in adjusted position by nuts on both ends.

Each gear 13 is also provided with an individual guard 30 adjustable about a pivot stud 23 as the line between this stud, the center of the gear 13, and the shaft 8 is broken to adjust for different sized rolls. Each 70 guard 30 is tangentially hinged to a supporting plate 31 and provided with a spring hinge 32 to hold it in and allow it to be swung out by hand. The plate 31 is swiveled on the stud 23 but fixed in adjusted position to the 75 frame by a nut and doweled collar 26 on each end. The pinions 16 and their studs are adjusted in the slot 22. Then the collars 26 are applied and drilled for the dowels 33 which are afterwards inserted, making everything firm. Without removing the nut, the 80 guard 30 can be swung out and the gear adjusted because of an opening 35 in which the nut on that end of the stud is located.

Now it will be seen that the intermediate 85 gear 11 practically never has to be changed and the shaft 10 therefore does not have to be adjusted. There is no adjustment of these parts and the various difficulties encountered by such adjustments are entirely eliminated. The pinions 16 are in perfect mesh with the intermediate gear 11 at all times. When the 90 rollers 14 are changed, the pinions 16 are at the same time adjusted, and instead of having a number of heavy gears 11 to manipulate 95 and store, only one and a series of small pinions 16 constitute all the parts. They are easily set at the time of assembling the machine by means of the nuts on the studs 23 and their setting at the time of changing the 100 print rollers 14 requires no adjustment except the loosening of the bolts 20 and the adjustment of the screw 21 to get them in perfect 105 mesh with gears 13. As a matter of fact, a great many sizes of rollers 14 can be accommodated in this way. These adjustments are 110 much simpler than the adjustment of the shaft 10 and the replacement of the gear 11 which is entirely eliminated by this invention. The studs 23 are held firmly and the 115 gears 16 fully guarded by the cover plate 25. The pinions are adequately guarded by individual adjustable guards 30. A simple and 120 convenient speed change arrangement is provided.

Although we have illustrated and described only one form of the invention, we are aware of the fact that modifications can be made therein by any person skilled in the art without departing from the scope of the invention as expressed in the claims. Therefore, we do not wish to be limited to all the details of construction herein shown and described, but what we do claim is:—

1. In a color printing machine, the combi- 125

- nation with a main cylinder and a series of color rollers mounted to contact therewith, of an intermediate gear centered on the same axis as the cylinder, means for driving said gear, a series of pinions for driving the color rollers from the intermediate gear, all adjustable as a whole circumferentially, and means for preventing their adjustment radially. 5
2. In a color printing machine, the combination with a main cylinder mounted to rotate freely, an intermediate gear adapted to rotate on an axis concentric with the cylinder, a gear in stationary bearings, and a pinion meshing with the last named gear for driving the intermediate gear, of a series of pinions meshing with the intermediate gear, a series of color rollers contacting with the cylinder and each having a driving gear 10 meshing with one of said pinions, each of said pinions being located in the area between the center of the intermediate gear and the circumference of one of the roll driving gears, and means whereby said pinions can be adjusted circumferentially to drive color roll gears of different sizes. 15
3. In a printing machine, the combination with a main cylinder mounted to rotate freely and a series of color rollers mounted to contact with the cylinder, of an intermediate gear rotatable on the shaft of the cylinder, means for driving the intermediate gear, an arcuate gear guard adjustable circumferentially, a series of pinions mounted under said 20 guard and meshing with the intermediate gear and with the gears of the color rollers, said guard extending over the teeth of the intermediate gear, and means for holding said guard in adjusted positions. 25
4. In a multicolor printing machine, the combination with a platen cylinder and a concentric series of color rollers mounted to contact therewith, of a permanent intermediate gear centered on the same axis as the cylinder, a series of pinions for driving the color rollers from the intermediate gear, a sector shaped sub frame centered on the axis of the cylinder and adapted to be adjusted about and held, and an arcuate cover frame carried by the 30 sub frame and extending over the pinions to protect their teeth and to provide a support for the studs of the pinions. 35
5. In a multicolor printing machine, the combination with a platen cylinder and a concentric series of color rollers mounted to contact therewith, each having a driving gear, of a permanent intermediate gear centered on the same axis as the cylinder, a series of pinions for driving the color rollers from the 40 intermediate gear, an arcuate guard for the pinions and the teeth of the intermediate gear, and a series of separate guards for the roll gears. 45
6. In a textile color printing machine, the combination with a main cylinder, a series 45
- of color rollers mounted to contact therewith, and a driving gear on each roll, of an intermediate gear centered on the same axis as the cylinder, means for driving said intermediate gear, a series of pinions for driving the color rollers from the intermediate gear, said pinions being circumferentially adjustable to permit the use of different sized rolls, and individual guards for the driving gears, each held at the center of a pinion and pivotally 50 adjustable thereabout. 55
7. The combination with a printing roll, its driving gear and a pinion adjustable laterally for driving the gear, of a guard for the gear comprising a plate swiveled concentrically with a pinion, a guard plate pivoted to the plate on a tangential axis, and means for yieldingly holding the guard in place. 60
8. In a color printing machine, the combination with a main cylinder mounted to rotate freely for receiving the textile material to be printed, and a series of color rollers mounted to contact with the material on the cylinder, of a permanent intermediate gear free on the shaft of the cylinder, a gear, a tilting and sliding frame, two relatively fixed gears movable with the frame, to bring one of them into or out of mesh with said gear, another gear on the frame, whereby when the frame is tilted to one side the intermediate gear will be driven by the single gear and by the double gear when tilted to the other side at a different speed, and a series of pinions meshing with the intermediate gear and with the gears of the color rollers. 65
9. In a textile printing machine, the combination with a main frame, and cylinder mounted to rotate freely, of an intermediate gear concentric with the cylinder, a series of pinions meshing with the intermediate gear, a series of color rollers contacting with the cylinder and each having a driving gear meshing with one of said pinions, means whereby said pinions can be adjusted circumferentially to drive color roll gears of different sizes, two frames adjustable on the main cylinder and having slots, studs for said pinions passing through the slots and dowelled collars on the studs to hold them in adjusted positions on the frames. 70
